DEVICE FOR OVERCOMING EFFECTS
OF SHOCKSFrank G. Logan, Mount Vernon, N. Y., assignor to
Ward Leonard Electric Company, a corporation
of New York

Application May 12, 1943, Serial No. 486,689

6 Claims. (Cl. 74—2)

This invention relates to mechanisms, such as electric switches and the like, which are movable to different positions, such as the open and closed position of a switch, circuit breaker, relay or other devices, and restrained in one of the positions by a latch or otherwise. Such mechanisms are released by a controlled movable element which is adapted to engage and release the latch or other restraining means upon the occurrence of a certain condition or certain conditions. For example, an overload relay is adapted to attract its movable armature or plunger and release the restraining means upon the occurrence of an overload current.

Mechanisms of this character when used in locations which are subject to mechanical shocks or jars are likely to be tripped or released by causing the movable element to be thrown against the releasing means and thereby cause an undesired tripping of the mechanism. It has been proposed to overcome this undesired action by providing an additional movable element which is normally at rest but which, under shock, would strike the restraining latch on the opposite side of the pivot of the latch from that engaged by the movable element of the mechanism and thereby prevent the latch from being tripped. However, in many cases the weight or mass of the counter-acting element required to overcome the effect of the force of the tripping element is quite considerable, resulting in considerably increasing the total weight of the parts and the space occupied.

By the present invention, instead of attempting to provide a movable mass sufficient in the force exerted thereby to overcome the force of the movable releasing element, a movable device is utilized which is controlled by the movement of a comparatively small mass which serves to lock the restraining means against release under shocks. That is, in the case of a restraining latch, the small movable mass causes an element to be moved to a position which will prevent the release of the latch.

The main object of the invention is to provide means for overcoming the effects of shocks which will be simple in character, of comparatively small weight and size and dependable in operation. Another object is to provide means which may be applied readily to various types of mechanisms without the necessity of radical change in the design of the parts and which, in some cases, may be added to existing mechanisms. Another object is to produce an auxiliary device which may be made at small cost and readily assembled. Other objects and advantages will be understood

from the following description and accompanying drawings which illustrate one embodiment of the invention applied to a relay.

Fig. 1 is a side view partly in section showing the parts in their restrained position; Fig. 2 is a vertical section of a portion of the parts showing them in their released position; Fig. 3 is a top plan view of a portion of the relay with one of the parts broken away; and Fig. 4 is a vertical section on the line 4—4 of Fig. 3.

The particular relay shown is of the type disclosed in the Kouyoumjian Patent No. 2,308,660 granted January 19, 1943 and forms no part of the present invention. It is sufficient to explain for present purposes that it has a magnet frame 1 and an exciting winding 2 which when sufficiently energized will attract and raise a movable element 3. This then moves the rod 4 upwardly which trips the pivoted latch 5 and releases the restrained element 6. This is a contact element biased to open position by a spring 7 tending to separate its movable contact 8 from the fixed contact 9. After opening, the contacts may be reclosed manually against the pressure of the spring 25 by the handle 10. The parts are then restrained in closed position by the latch 5 which engages a disk 11 fixed to the rod 6. Instead of closing contacts in the restrained position, the device may be arranged to open contacts in the restrained 30 position and close them in the released position or variously control contacts in the different positions; or the controlled element may serve to actuate any mechanical means for any desired purpose. Instead of using an electromagnet for 35 tripping the holding means, any other form of device having a movable element may be used for releasing the restrained element.

It is apparent that the movable element 3 and the rod 4 may be actuated, under mechanical 40 shocks or jars imposed upon the device, to move upwardly with reference to their support and thereby actuate the latch to release the parts. Such an improper actuation of the releasing means would be highly undesirable because the 45 parts should be released only when the predetermined conditions occur for such release by sufficient energization of the magnet. Any improper release of the restrained parts is avoided by the present invention.

Fig. 1 shows the parts in the restrained position, the latch 5 being biased to latching position by a spring 12 encircling the shaft on which the latch is mounted which spring has extending portions tending to turn the latch in a clockwise 55 direction. A stop 12a turned up from the metal

plate 13 serves to limit the movement of the latch in a clockwise direction when released from the disk 11. This positions the inclined end of the latch so that it will be readily reengaged by the disk 11 when moved to the position shown in Fig. 1. The metal plate 13 is provided with two upwardly extending portions 13a, 13b for guiding the rod 6. The plate 13 also is provided with a horizontally extending portion 13c, as shown in Fig. 3, which has an upwardly extending terminal connection 13d. A flexible lead 14 connects the plate 13c electrically with the rod 6. The fixed contact 9 is supported by a flexible leaf spring 9a which in turn is connected electrically to a terminal 9b mounted upon the base 15 of insulating material. A pin 16 is fixed to the rod 6 and extends downwardly into a slot formed between a pair of upwardly extending portions 15a from the base 15. The pin 16 in its movement in this slot serves to guide the contact end of the rod 6; and when the parts are released, the pin 16 serves as a stop to limit the outward movement of the rod 6 by engaging the plate portion 13b.

The means for overcoming the effects of shocks and preventing the improper release of the restrained parts is shown in the present instance as comprising a cross piece 17 of insulating material which, as well shown in Fig. 4, is supported at its opposite ends by sleeves 18 of insulating material, the parts being secured to the base 15 by the screw bolts 19. Instead of making the cross bridge and supporting sleeves of insulating material, they may be made of metal if desired.

A central portion on the underside of the bridge 17 is cut away, as shown in Figs. 2 and 4, and a weight or mass 20 extends partially within the opening. This mass is pivotally mounted at its inner end on a rod 21, the ends of which rod are supported by extending within the bridge 17. Fixed to the inner end of the mass 20, or forming a part thereof, is a downwardly extending plate 20a which passes by the rod 6 and is provided with a tongue or extension 20b, as well shown in Fig. 4. The normal position of the extension 20b is above and beyond the inner end or tail of the latch 5, as shown in Fig. 2 and in full lines in Fig. 1. The weight of the mass 20 normally holds the extension 20b in this position against the portion 13b of the metal plate.

It is therefore apparent in the absence of any shocks, the projection or element 20b is out of the path of movement of the tail of the latch, permitting the latch to be tripped by the upward movement of the element 4 upon the occurrence of a predetermined condition, such as an overload current in the relay. When, however, a mechanical shock or series of shocks, occurs which would impart an upward movement to the element 4 and thereby improperly trip the latch, the mass 20 and the element 20b serve to prevent such improper release of the parts. This is due to the fact that any mechanical shock which would move the rod 4 and plunger 3 upwardly, would likewise move the mass 20 upwardly, turning on its pivot in a clockwise direction and thereby bringing the element 20b over the tail of the latch and prevent its tripping by the movable element of the relay. Also, the distance from the pivot of the mass to the lower end of the locking element 20b is greater than the distance from the pivot of the mass to the center of gravity of the mass which results in a comparatively small movement of the mass, giving an amplified movement of the locking element over

the tail of the latch. It follows that the latch will thus be locked against release before it is subjected to the impact of the movable element of the relay; and the parts are related so that only slight movement of the element 20b from its normal position is required to arrive at a locking position over the tail of the latch. Fig. 1 shows in dotted lines the extreme locking position of the mass and its locking element but it is apparent that the latch will be locked from disengagement as soon as the edge of the locking element passes over the edge of the tail of the latch. After the passage of the shock or shocks the mass 20 will fall to its normal position and swing the locking element out of the path of the latch, thus permitting the relay to function in its intended manner upon the occurrence of an abnormal condition, such as an overload current.

The parts may be variously arranged in their relationship to each other for attaining the objects of the invention and adapted to various types of devices which are restrained in one position and biased to move to another position when the restraining means is released by a movable element.

Although a particular embodiment of the invention has been described, it will be understood that various modifications may be made for adaptation to particular requirements without departing from the scope of the invention.

I claim:

1. The combination of a movable device biased to move from a restrained position, means for holding the device in the restrained position against its biased movement, an element movable independently of said means for releasing said means, said element being subject to movement by mechanical shocks, means for actuating said element for releasing said holding means, and means having a pivotal support movable under shock for locking said holding means from movement by said movable element until the passage of the shock.
2. The combination of a movable device biased to move from a restrained position, means for holding the device in the restrained position against its biased movement, an element movable independently of said means for releasing said means, said element being subject to movement by mechanical shocks, means for actuating said element for releasing said holding means, a fixed support, and an element movable under shock to a position supported between said fixed support and said holding means for locking said holding means from movement by said first named movable element until the passage of the shock.
3. The combination of a movable device biased to move from a restrained position, means for holding the device in the restrained position against its biased movement, an element movable independently of said means for releasing said means, said element being subject to movement by mechanical shocks, means for actuating said element for releasing said holding means, a fixed support, and a mass pivotally mounted on said support having an extension movable therewith under shock for locking said holding means from movement by said movable element until the passage of the shock.
4. The combination of a movable device biased to move from a restrained position, means for holding the device in the restrained position against its biased movement, an element movable independently of said means for releasing said means, said element being subject to movement

by mechanical shocks, means for actuating said element for releasing said holding means, a fixed support, and a mass pivotally mounted on said support having an extension movable therewith under shock for locking said holding means from movement by said movable element until the passage of the shock, the distance from the center of gravity of said mass to its pivot being less than the length of said extension.

5. The combination of a movable device biased to move from a restrained position, a latch for holding the device in the restrained position against its biased movement, an element movable independently of said latch for tripping said latch, said element being subject to movement by mechanical shocks, means for actuating said element for releasing said latch, a fixed support, and a mass pivotally mounted on said support having

10 an extension movable therewith under shock for locking said latch from movement by said movable element until the passage of the shock.

6. The combination of a movable device biased to move from a restrained position, a latch for holding the device in the restrained position against its biased movement, an element movable independently of said latch for tripping said latch, said element being subject to movement by mechanical shocks, means for actuating said element for releasing said latch, a fixed support above said latch, and a mass pivotally mounted on said support having a downward extension movable therewith under shock over the tail of the latch for locking the latch from movement by said movable element until the passage of the shock.

FRANK G. LOGAN.
